UNITED STATES PATENT OFFICE.

WILLIAM T. JOHNSTON, OF OTTUMWA, IOWA.

IMPROVEMENT IN RUFFLING ATTACHMENTS FOR SEWING-MACHINES.

Specification forming part of Letters Patent No. 131,277, dated September 10, 1872.

To all whom it may concern:

Be it known that I, WILLIAM T. JOHNSTON, of Ottumwa, in the county of Wapello and State of Iowa, have invented a new and Improved Gathering Attachment for Sewing-Machines; and I do hereby declare that the following is a full, clear, and exact description thereof, reference being had to the accompanying drawing making part of this specification, in which—

Figure 1 is a view of one side of the device as it appears when the needle-bar is raised to its highest point. Fig. 2 is a similar view of the same parts shown in Fig. 1 as they appear at the termination of the lower stroke of the needle-bar. Fig. 3 is a perspective view of the device.

Similar letters of reference indicate corresponding parts in the several figures.

This invention relates to improvements on mechanism designed for gathering or ruffling; and consists in an adjustable vibrating yoke between which the head of the needle-binding screw on the needle-bar plays in combination with a gathering-slide and a pressure foot, as will be hereinafter explained.

The following description of my invention will enable others skilled in the art to understand it.

In the accompanying drawing, A A' represent the frame of the device, to one end of which a pressure-foot, B, is secured. To the standard portion, A', of the frame a vertically-vibrating yoke is pivoted at g, which yoke consists of two curved arms, C C', and a connecting-plate, a. The plate a is pivoted, at e, to the free end of the lower arm C, and connected to the upper arm C' by a movable pin, which allows the ends of the arms to be adjusted nearer together or further apart, according to the length of strokes which it is desired to give to the gathering-slide n. The gathering-slide is a thin forked piece of metal, slightly curved, and secured to an arm, h, so as to work beneath the pressure-foot B and against the bottom side thereof. The arm h is pivot-

ed, at i, to an extension, f, of the yoke-arm C', so that as the yoke is moved up and down the slide n will receive a reciprocating motion, the length of the strokes being regulated by the connecting-pin of plate a, as above explained.

The device above described, if detached from the pressure-foot B of a sewing-machine, may be secured to the cloth-plate, or it may be secured to the overhanging bracket of a sewing-machine, provided always the slide n be adjusted to work between the pressure-foot and the cloth-plate, and the head of the needle-screw on the needle-bar be arranged between the two arms C C' so as to alternately strike them.

It will be seen from the above description that my gathering device is operated by the rise and descent of the needle-bar, and that the needle passes through the gather last formed and holds it before the slide n is caused to recede from such gather.

Having described my invention, what I claim as new, and desire to secure by Letters Patent, is—

1. The adjustable vibrating yoke, consisting of arms C C', having a common pivot, g, whose free ends are connected by means of the plate a, the upper arm being attached by its arm f and an arm, h, to the gathering-slide n, substantially as described.

2. A vibrating yoke, within which a projection on the needle-bar plays, consisting of two arms, C f and C', pivoted at g, in combination with a gathering-slide, n, and a pressure-foot, B, substantially as described.

3. The arms C C', carrying a gathering-slide, n, and connected by the adjustable plate a, substantially as and for the purpose described.

Witness my hand in the matter of my application for Letters Patent for gathering attachment for sewing-machines.

WILLIAM T. JOHNSTON.
